Application September 28, 1940, Serial No. 358,903

10 Claims. (Cl. 282—5)

The present invention relates to manifolding. In manifolding machines, it has been customary to provide strip-advancing means, such as a plurality of feed disks cooperating with feed rollers, for feeding a plurality of superposed form lengths of manifolding stationery over a platen, transfer sheets interleaved therewith permitting data inscribed on the topmost sheet to be recorded on the underlying strips. In order to register the superposed form lengths of the strips, feed-arresting form-registering apertures were provided in the strips in alignment with the feeding means to interrupt advancement of the strips and to effect registration thereof. Restarting means for moving said apertures beyond the bite of the feeding means was also provided for resuming advancement of the strips.

It is often desired for record purposes to transfer only a portion of the data recorded on each form length of certain of the manifolding strips to one or more of the underlying strips, the latter being known as summary strips. In general, as the other strips, bearing the complete data, hereinafter called worksheet or detail strips, are advanced a form length at a time by the feeding mechanism, it is desired to advance the summary strip by a smaller distance sufficient merely to bring a fresh space below that portion of the detail strips which is provided for receiving the data to be recorded on the summary strip. To avoid transfer of the remaining data inscribed on the detail strips to the summary strip, the latter is generally separated from its superposed transfer sheet by a masking plate having an aperture in the desired position for permitting said transfer sheet to contact the summary strip over a limited area, or else the transfer sheet is so shaped and located as to extend merely over the desired portion of the summary strip.

It is an object of the present invention to provide a manifolding register having a main feeding means adapted to advance a plurality of detail strips form-length distances and to interrupt the advancement of said strips by entering feed-arresting, form-registering physical alterations therein during each form-length feeding operation for registering the superposed form lengths thereof, said register having also auxiliary means for engaging the detail strips as well as a summary strip, included therewith, for resuming advancement of the detail strips to move the said feed-arresting, form-registering alterations beyond the bite of the main feeding means, and simultaneously to advance the summary strip

through the desired distance during each form-length feeding operation.

In the form of the invention illustrated herein as exemplary thereof, feeding means for advancing a plurality of continuous superposed detail strips, cooperates with marginal physical alterations in each form length thereof to arrest the advancement of said strips during each form-length feeding operation, for registering the superposed form lengths before a transverse severing line between successive form lengths reaches a predetermined severing station on the machine. Auxiliary feeding means are provided to resume said strip advancement, moving said marginal alterations beyond the bite of the main feeding means and cooperating with intramarginal alterations in said strips to again interrupt the advancement thereof for accurately registering the superposed form lengths by the time said severing line attains the predetermined severing station. The main feeding means releases the strips during said second registration and reengages said strips by the time the severing line reaches the severing station. The summary strip is made sufficiently narrow not to be engaged by the main feeding means but only by the auxiliary feeding means which advances the summary strip through the desired distance and the detail strips simultaneously during the portion of the feeding operation in which the detail strips are advanced by the auxiliary feeding means.

The machine preferably includes separate tensioning means for each of the superposed strips, whereby the summary strip and each of the detail strips may be independently advanced by the said feeding means.

The use of the auxiliary feeding means to accomplish the dual function of advancing a summary strip as well as to resume advancement of superposed detail strips, permits the use of a summary strip without any additional parts being required in the feeding mechanism and results in a simpler, cheaper, and more effective construction than any heretofore known.

Other features and advantages will appear hereinafter from the following description referring to the accompanying drawings which illustrate one embodiment of the invention, that at present preferred, in which:

Figure 1 is a top or plan view of a manifolding machine according to the invention, with a number of superposed detail strips and a summary strip shown in their relative positions, portions of said strips and machine being cut away

to show the details of the underlying strips or mechanism.

Fig. 2 is a cross-sectional view of the machine substantially along the line 2—2' of Fig. 1.

Fig. 3 is a detail in perspective of a portion of the feeding mechanism in its final position after feeding one form length of detail strips and after advancing the summary strip the desired distance, this being also the initial position for feeding the succeeding form length of manifolding stationery, the position of the latter being indicated by dotted lines.

Fig. 4 is similar to Fig. 3, but shows the relation of the feeding mechanism and the manifolding strips as advancement of the detail strips by a main feeding means is first halted during a form-length feeding operation for registration of said strips.

Fig. 5 is also similar to Fig. 3, but shows the relative position of the mechanism and manifolding stationery during advancement of the summary strip by the auxiliary feeding means, the latter having resumed and again interrupted advancement of the detail strips for accurately registering them, and the main feeding means having released said strips to permit registration thereof.

Fig. 6 is likewise similar to Fig. 3, but shows the position of the feeding mechanism during the concluding portion of the advancement of the summary strip by the auxiliary feeding means, the main feeding means being on the point of reengaging the detail strips.

Fig. 7 is an enlarged fragmentary detail in cross-section substantially along the line 2—2' of tensioning means for applying separate retarding tension to the superposed strips of manifolding stationery.

Referring to the accompanying drawings, the manifolding register is shown as comprising a casing having a bottom wall 10, side walls 11, and front and rear end walls 12 and 13, inwardly extending vertical flanges 14 carried by a pair of vertical plates 15, inwardly spaced from the side walls at the front end of the register, forming a supply compartment 16 for receiving a pack 17 of zigzag-folded multiple manifolding stationery, comprising a plurality of superposed detail strips 18.

In the upper portion of the supply compartment 16, a second zigzag folded pack 19 of a continuous summary strip 20, which is materially narrower than the detail strips, is carried by a horizontal plate 21 having lateral upturned flanges 22 for positioning said pack, said plate being supported at one end by ears 23 lanced from the plate 15 and at the other end by pins 24 carried by plates 15 and pivotally engaging flanges 22.

The detail strips 18 are successively led over a transverse guide roller 25 and a plurality of guide rollers 26, and the summary strip 20 is led over a similar roller 26a to a position overlying a platen 27. The summary strip forms the lowermost member of the superposed strips of manifolding stationery and is substantially centrally positioned with respect to said detail strips 18 so that the margins of the latter extend beyond the edges of the summary strip. The platen 27 is pivotally attached by means of clips 28 to a transverse rod 29 and supported upon the upper edges of plates 15.

A plurality of transfer or carbon sheets 18a anchored by suitable means known in the art at the receiving end of the platen 27 are inter-

leaved with the superposed detail and summary strips.

From the platen 27, the superposed strips 18 and 20 pass through a feeding mechanism M at the delivery end of said platen. A deflector plate 30 ahead of the feed mechanism separates the detail strips 18 from the summary strip 20, the former passing outward above said deflector plate over the cover 31 of a record strip storage compartment 32 in front of the feed mechanism M, while the summary strip 20 is deflected downward below said plate into the record storage compartment where it is preferably refolded into a zigzag folded pack 33 as shown. The cover 31 is hinged at 34 to the front wall 12 of the casing so that it may be raised to permit removal of the pack 33 of the summary strip.

A cover or margin plate 35, having an inscription opening above the platen 27 is hinged at 36 to the rear end wall 13 of the casing and extends over the feed mechanism M. In order to provide means for severing issued detail strips, the said margin plate or other part of the register is preferably provided with a tearing edge 37 in front of the feed mechanism above the deflector plate 30.

Tensioning means shown in detail in Fig. 7 is also provided to apply an equal frictional retarding tension to each of the manifolding strips 18 and 20, whereby the said strips may be moved independently of each other when engaged by the feeding mechanism. This means comprises a thin tension plate 38 loosely carried by each of the guide rollers 26 and extending for support a short distance over the receiving end of the platen 27. These tensioning plates are interleaved with the manifolding strips 18 and 20 and are compressed against the surface of the platen by a spring clip 39 secured to the lower surface of the cover plate 35.

For the purpose of preventing marginal alterations, shown as notches, in the detail strips from catching on the forward edges of the anchoring means of the transfer sheets 18a, a pair of flaps 40 of smooth fabric may be secured at each end to the rollers 26 and extend above and below the forward ends of each of the transfer sheets 18a. By this means, the said marginal alterations are prevented from catching on the said transfer sheets, insuring smooth advancement of the strips onto the platen.

The feed mechanism M is supported by a pair of vertical bearing plates 41 disposed adjacent either side of the casing. A rotary operating shaft 42 journaled in said plates extends through one side of the casing and carries a crank 43 adapted to be manually rotated by means of a handle 44. A roller shaft 45 is carried above the shaft 42 in vertical slotted extensions of said bearing plates. The operating shaft 42 carries a pair of main feed disks 46 adjacent said bearing plates and aligned with physical alterations in the detail strips 18 adjacent the margins thereof. Inwardly of the main feeding disks 46, the rotary shaft 42 carries a pair of auxiliary feed disks 47 for engaging the narrower summary strip 20 as well as the detail strip 18, said auxiliary feed disks being aligned with intramarginal apertures in the detail strips.

The roller shaft 45 carries a pair of frictional feed rollers 48 aligned with main feed disks 46 and a pair of inwardly spaced feed rollers 49 aligned with the auxiliary feed disks 47. The feed rollers may be suitably knurled as shown to increase the frictional engagement thereof with

manifolding stationery in contact therewith. The roller shaft 42 is normally urged downward by springs, not shown, but well known in the art, whereby rollers 48 and 48' and disks 46 and 47 are adapted to grip strips of manifolding stationery inserted between them. Means, not shown, for releasably separating said rollers and disks, including the lever 49, are provided in the manner known in the art in order to facilitate threading of the manifolding stationery through the feeding means. The rotary shaft 42 and the roller 45 are connected by gears 50 in such a manner as to render the peripheral speed of disks 46 and 47 the same as that of the rollers 48 and 48' upon rotation of the feeding mechanism.

The detail strips 18 are divided into a series of form lengths by transverse severing lines 51 which may be conveniently weakened by perforations to facilitate severing and folding of the strips. The multiple detail strips 18 are preferably folded into a zigzag folded pack along said severing lines.

Each form length of the detail strips is provided with feed-arresting form-registering alterations adjacent the margins thereof. These alterations are shown as triangular notches 52, the forward edge of which coincides with the severing line 51 between each successive form length and the trailing edge of which extends into the head of the succeeding form length. Upon entering these notches, which are longitudinally aligned with feed disks 46 and corresponding rollers 48, the said feed disks and rollers, which constitute the main feeding means, become inoperative to advance the strips until the notches are moved beyond the bite of the feeding means. Engagement of the feed disks and rollers with the notches tends to effect registration of the superposed form lengths of the strips, especially in longitudinal direction.

As hereinbefore stated, the summary strip 20 is narrower than the superposed detail strips 18 and is centrally positioned below the latter in such a manner that the summary strip is not engaged by the main feed disks 46 and corresponding rollers 48, but by disposition of the feed disks in such a manner as to engage the detail strips adjacent the margins thereof, a relatively wide summary strip may be used of such breadth that it extends substantially to the limits of the writing space in the detail strip form lengths. All of the strips, however, are adapted to be engaged by a shoe 53 carried by the auxiliary feed disk 47 and corresponding rollers 48, said shoe and roller constituting an auxiliary feeding means, the latter feeding means being spaced inwardly from the main feeding means. The auxiliary feed disks 47 are of smaller diameter than the main feed disks 46, but the arcuate feeding surface 53a of the shoe 53 is adapted in cooperation with the corresponding roller 48' to grip the superposed strips when said shoe attains a position directly below said roller. Thus during each revolution of the operating shaft 42, the auxiliary feeding means is adapted to engage the strips 18 and 20 only during passage of the arcuate surfaces 53a below the aligned rollers 48'.

The summary strip 20 contains no feed-arresting alterations and thus is advanced a distance corresponding to the length of the arcuate surface 53a for each revolution of the shaft 42. The detail strips, however, are preferably provided with intramarginal feed-arresting, form-registering apertures 54 longitudinally aligned with the auxiliary feeding means and disposed in

each form length behind the marginal notches 52. Thus upon engaging the superposed strips 18 and 20, the auxiliary feed disks 47 advance the detail strips sufficiently to move the notches 52 beyond the bite of the main feed disks 46 and corresponding rollers 48, but upon entering the intramarginal apertures 54, the feed disks become inoperative to further advance the detail strips 18, although advancement of the summary strip 20 is continued more or less depending on the length of the feeding surface of the disks 47 which may be predetermined in accordance with the length of the desired summary feed.

In order to permit entrance of the auxiliary feed disks 47 into apertures 54 to interrupt advancement of the detail strips 18 and to accurately register the superposed form lengths of said strips, the main feed disks 46 are provided with cutaway portions 55 transversely aligned with the auxiliary feeding shoes 53 in such a manner that the main feeding disks 46 are incapable of engaging the detail strips from the time the feed shoes 53 initially engage the manifolding strips until after the feed shoes enter the apertures 54. Thus, as the auxiliary feeding means enters said apertures, the detail strips are released by the main feeding means and the superposed form lengths thereof are accurately registered in transverse and longitudinal direction by the auxiliary feeding means. This accurate registration occurs preferably just before the transverse severing line between successive form lengths attains the severing station 37. Hence, as the cutaway portions 55 are moved beyond the rollers 48, the main feed disks 46 reengage the detail strips 18, notches 52 having been advanced beyond the bite of said disks and rollers, and the strips are moved forward by a small increment to bring a severing line 51 between successive form lengths below the tearing edge 37. As an issued form length of the detail strips 18 is severed along the said line, engagement of the disks 46 and rollers 48 with the strips prevents disalignment of the succeeding form length positioned above the platen 27.

Releasable stop means are provided to arrest rotation of the feed mechanism automatically as the said severing line reaches said tearing edge. The said stop means may be of any suitable construction, various forms of which are well known in the art.

The length of each form of the detail strips 18, as shown, is less than the operative peripheries of the main feed disks 46. Thus, one revolution of the operating shaft 42 is effective to feed the said strips by one form length. Moreover, this arrangement insures that advancement of the strips will be interrupted by entry of the feed disks 46 into notches 52 before the auxiliary feed disks 47 become operative to resume the advancement.

Each form length is provided with a transverse space as indicated at 56 in Fig. 1 for recording a summary of the transaction inscribed in detail on the remainder of the detail strip form length. For instance, as shown, said space may include subspaces for recording the number of the ticket, the amount of a sale, date, purchaser, and salesman. The breadth of the summary space in longitudinal direction is equal to or less than the peripheral feeding surface 53a of the auxiliary feed disks 47. Thus, upon each revolution of the shaft 42 for positioning a new form length of the detail strips 18 for inscription above the platen 27, the summary strip 20 is advanced by a dis-

tance equal to or greater than the breadth of the space 56 in the detail strip and as each transaction is recorded in said space, it is transferred to a fresh line of the summary strip 20 which is positioned below it.

In order to avoid transfer of the details of each transaction, which is recorded in the upper portion of each form length of the detail strips, to the already inscribed portions of the underlying summary strip, the transfer sheet 18a between the said summary strip and the lowermost detail strip may terminate at the upper margin of the space 56, if the latter is at the lower end of the detail strip form length, when the said space occupies its normal position at the end of each form-length feeding operation. Otherwise, a suitably anchored masking plate having an aperture in a position corresponding to that occupied by the space 56 at the end of each form-length feeding operation may be inserted between the summary strip 20 and the lowermost transfer strip 18a in the manner well known in the art.

Obviously the consecutive "form lengths" of the summary strip 20 are not related to the transverse folds therein which are used merely to fold them into a zigzag pack 19. The alignment of the strip 20 is not controlled by feed-arresting form-registering apertures.

Figs. 3 to 6 inclusive show the consecutive positions of a main feed disk 46 and an auxiliary feed disk 47 carried by the operating shaft 42, said disks being aligned respectively with feed rollers 48 and 48', and the relative positions of a summary strip 20 and superposed detail strips 18 during the feeding of one form length of the latter. Operation of the machine is as follows:

In Fig. 3, the detail strip is in its initial or final position for one form-feeding operation. The transverse severing line 51 between successive form lengths 18b and 18c of the detail strips 18 is positioned below the tearing edge 37. The auxiliary feed disk 47 has advanced marginal notches 52 in the detail strips just beyond the bite of the feed disk 46 and corresponding roller 48 and has accurately aligned said strips by entering apertures 54 while the main feed disk 46 was inoperative to engage said strips because of cutaway portion 55, the auxiliary feed disk becoming inoperative thereafter to continue advancement of the detail strips. Cutaway portion 55 on disk 46 has moved just beyond the corresponding roller 48, so that the feeding surface of the main feeding disk 46 has just reengaged the detail strips 18 adjacent the margin to bring the severing line 51 to the tearing edge 37.

The summary strip 20 which is positioned below the detail strips and which is sufficiently narrower than the latter to avoid engagement by the main feed disks 46 has been advanced by a distance equal to the length of the feeding surface 53a of the shoe 53 and the latter is about to move beyond the corresponding roller 48' for releasing the summary strip. The advancement of the summary strip 20 has brought a fresh line thereof below the summary space 56 on the form length 18c of the detail strip in the final position which it occupies. The automatic stop means cooperating, for instance, with crank 43, has arrested rotation of the feeding mechanism.

Issued form lengths 18b of the detail strips may be torn off along tearing edge 37, if desired, for distribution. Form length 18c positioned above the platen 27 may be inscribed with details of the next transaction, the summary of the re-

corded data being written in the space 56 provided therefor. As hereinbefore described, the latter data is transferred to the fresh space on the summary strip 20, while transfer of the detail record on the other portions of the detail strip to the underlying summary strip is avoided by limiting the length of the summary transfer sheet or by providing suitable masking means for the latter.

After the inscription is complete, the crank 43 is rotated causing feed disk 46 and roller 48 to advance form length 18c through the feeding mechanism while summary strip 20 remains stationary, any tendency thereof to be moved by friction of the detail strips 18 being overcome by the tensioning means provided at the receiving end of the platen.

However, as the main feed disk 46 and co-operating roller 48 enter notch 52 in form length 18d as shown in Fig. 4, the advancement of the detail strips is arrested and a degree of registration of the superposed form lengths thereof, especially in longitudinal direction, is effected.

Upon continued rotation of the feeding means by the crank 43, cutaway portion 55 of the disk 46 moves below corresponding roller 48 rendering the main feeding means inoperative to grip the detail strips 18. Meanwhile the shoe 53 carried by auxiliary feed disk 47 and roller 48' have engaged detail strips 18 as well as summary strip 20, advancing all of the strips until said shoe enters aperture 54 in the form length 18d of the detail strips, as shown in Fig. 5. This advancement moves notch 52 beyond the bite of feed disk 46 while engagement of shoe 53 with apertures 54 again interrupts advancement of detail strips, accurately registering the superposed form lengths thereof in longitudinal as well as transverse direction.

Continued rotation of the feed mechanism to the position shown in Fig. 6 permits the detail strips 18 to remain stationary, the main feed disks 46 being inoperative because of the cutaway portion 55, and shoes 53 being inoperative by reason of their engagement with apertures 54. However, advancement of the summary strip 20 is continued by shoe 53 and roller 48', the tensioning means at the receiving end of the platen 27 preventing the detail strips 18 from being displaced by friction with the said summary strip.

As one revolution of the feeding mechanism is completed, shoe 53 completes the advancement of the summary strip 20, as it once more reaches the position shown in Fig. 3 while the main feed disk 46 reengages the following form length 18d of the detail strips as cutaway portion 55 moves beyond the roller 48, the main feed disk moving the detail strips forward slightly to bring a severing line 51 below the severing station 37 on the machine. The automatic stop means, hereinbefore described, arrests motion of the crank 43 as the revolution is completed and the issued form length 18c may be severed for distribution, while form length 18d and a fresh line on the summary strip 20 are positioned above the platen 27 for inscription.

It is apparent that each revolution of the feeding mechanism advances the summary strip 20 into the storage compartment 32, below the deflector plate 30. Here, the said strip may be advantageously folded into a zigzag pile as shown.

Obviously, if desired, one or more of the detail strips 18 may also be fed below said deflector plate 75 and refolded into a separate pile in the storage

compartment 32, in order to provide a record copy of each form length of the detail strips, suitable additional space being provided in said storage compartment for receiving said pile.

Since the auxiliary feed disks are arrested in the same position in each revolution by the automatic stop means and since said disks no longer effect feeding of the detail strips after entering apertures 54, it is not essential that the feeding shoes 53 carried thereby should release the summary strip 20 at the end of each revolution of the operating shaft 42. In other words, it is immaterial whether each advancement of the summary strip corresponding to advancement of the detail strips 18 a form length at a time, should occur entirely during the latter part of said form-length feeding operation, or partly at the beginning and partly at the conclusion thereof. It is merely necessary that some portion of the summary strip feeding operation should occur while the notch 52 is positioned at the bite of the feeding means, in order that the auxiliary feeding means may also act as a restarting means for moving said notch beyond the bite of the main feeding means, thus enabling the latter to continue advancement of the detail strips.

The use of triangular marginal notches as feed-arresting form-registering alterations in the detail strips is preferred in view of the lesser number of dies required thereby in the manufacture of the manifolding strips, resulting in a material saving. However, other kinds of notches or apertures adjacent the margins of the detail strips may be used instead, provided that they lie beyond the limits of the narrower summary strip with which the detail strips are fed.

Disposition of said notches to coincide with the transverse severing lines 51 facilitates zigzag folding of the detail strips 18 into a pack, and also facilitates the severing of the issued detail strips along the said severing lines. However, the notches or apertures may be spaced from said severing lines without interfering with the operation of the manifolding machine.

Intramarginal apertures 54 in the detail strips must fall within the limits of the relatively narrower summary strip 20 used therewith in order that the auxiliary feeding means may perform its dual function of feeding the summary strip and accurately registering the detail strips.

Since the bite of the main and auxiliary feeding means is transversely aligned across the machine, the said intramarginal apertures in the detail strips must be positioned in each form length behind the marginal alterations therein in order that the latter may be moved beyond the bite of the main feeding means before the auxiliary feeding means becomes inoperative by reason of its entering the intramarginal apertures.

While the mechanism, as shown, is best adapted to feed one form length of the detail strips for each revolution thereof, the operative feeding peripheries of the main feeding disks being greater than a form length of the manifolding stationery, it is possible to operate the machine with detail strips having form lengths exceeding the total peripheries of the main feed disks, more than one revolution of the feeding mechanism being then required for each form-length feeding operation. At the same time, the summary strip is advanced by a multiple of the length of the arcuate feeding surface of the auxiliary feeding shoe 53.

Variations and modifications may be made within the scope of this invention and portions

of the improvements may be used without others.

I claim:

1. In the art of feeding a plurality of superposed continuous manifolding strips, divided transversely into a series of form lengths and having feed-arresting form-registering apertures in each form length, over a platen in a manifolding register having a feeding means aligned with said apertures, and cooperating therewith to arrest the advancement of the strips to effect registration thereof during each form-length feeding operation, and having also summary strip feeding means operated in timed relation with a main feeding means, the improvement which comprises copositioning a relatively narrower continuous summary strip together with the detail strips above said platen, the edges of the summary strip terminating short of said main feeding means, but a portion of said strip being aligned with said summary strip feeding means, whereby the summary strip is advanced a predetermined distance, less than a detail strip form length, solely by the summary strip feeding means during each detail strip form-length feeding operation and the detail strips are partially fed by said summary strip feeding means to advance the apertures therein out of feed arresting position whereupon the main feed is operative to advance said detail strip.

2. The method of feeding a pile of continuous manifolding material including superposed record strips divided into form lengths and a summary strip divided into lengths less than a form length disposed at the bottom of the pile and having its margins inwardly displaced from the margins of the record strips, comprising frictionally feeding the record strips a distance equal to the difference between a form length of the record strip and a length of the summary strip and rendering said feed inoperative to advance the record strips, and engaging the pile intermediate the margins of the summary strip with an auxiliary frictional feeding member and feeding the record and summary strips a distance equal to the length of the summary strip to complete the feed thereof and of the form length of record strip and rendering the frictional feeding of the record strips operative to again advance said record strips.

3. The method of feeding a pile of continuous manifolding material including superposed record strips having marginal feed-arresting form-registering apertures at predetermined intervals therealong and a summary strip disposed at the bottom of the pile and located laterally between the apertures, comprising engaging the margins of the record strips by rotatable frictional feeding means in alignment with the apertures, rotating said feeding means to advance the record strips until the feeding means enters the apertures to stop the feed thereof and register the strips, and subsequently moving a summary strip feeding means having an effective feed equal to the length of the summary strip into engagement with the summary strip to advance the summary strip and record strips a distance which is sufficient to complete the advance of the summary strip and move the record strips into frictional engagement with the first-mentioned feeding means so as to resume feed of the record strips.

4. The method of feeding a pile of continuous manifolding material including superposed record strips divided into form lengths and having marginal feed-arresting form-registering notches and longitudinally displaced intramarginal feed-

arresting form-registering apertures at form-length intervals therealong and a summary strip divided into lengths less than a form length disposed at the bottom of the pile and located laterally between the notches, comprising engaging the margins of the record strips by rotatable frictional feeding means in alignment with the notches, rotating said feeding means to advance the record strips until the feeding means enters the notches to stop the feed thereof and register the strips, and moving a summary strip feeding member disposed in alignment with the intramarginal apertures and having a feeding face equal to the length of the movement of the summary strip into engagement with the summary strip to advance the summary strip and record strips a distance which is sufficient to complete the advance of the summary strip and move the record strips into a position to be again frictionally engaged by the first-mentioned feeding means so as to resume feed of the record strips, the summary strip feeding member cooperating with the intramarginal apertures in the record strips to again register said strips prior to said resumption of feed thereof.

5. The method of feeding a pile of continuous manifolding material including superposed record strips divided into form lengths and a summary strip divided into lengths less than a form length disposed at the bottom of the pile and having its margins inwardly displaced from the margins of the record strips by a feeding means adapted to advance the strips a form length for each operation thereof comprising engaging and frictionally feeding the record strips alone for a distance equal to the difference between a form length of the record strip and rendering the feeding means inoperative to advance the record strips prior to a complete feeding operation; and subsequently engaging the bottom of the pile intermediate the margins of the summary strip, during continued operation of the feeding means, with an auxiliary feeding member having an effective feeding action equal to the length of the summary strip and frictionally advancing the summary strip and also the superposed record strips a distance sufficient to complete the advance of both strips and again render the frictional feeding of the record strips operative to advance the record strips alone upon the next operation of the feeding means.

6. In a manifolding register, a supply of stationery comprising a plurality of superposed continuous strips, certain of said strips having feed-arresting, form-registering physical alterations at predetermined intervals and being divided into a series of form lengths by transverse severing lines, and at least one of said strips being comparatively narrow and terminating short of said alterations in transverse direction; a platen for supporting said superposed strips; a main feeding means including a drive shaft positioned adjacent the platen and aligned with said physical alterations for advancing the first-named strips over said platen and cooperating with said alterations to interrupt advancement of said physically altered strips during each form-length feeding operation for registering the superposed form lengths of said strips; and means mounted on said shaft between the edges of said narrow strip and separate from said first-named feeding means for feeding said narrow strip independently of said other strips a distance less than a form length, said means having a feeding surface of a length corresponding to the extent of

feed required by said narrow strip to engage and frictionally feed said strip and being disposed on the shaft in relation to said first-named feeding means as to also move said first strips to bring the alterations beyond the main feeding means and resume the feed thereby.

7. In a manifolding register, a supply of stationery comprising a plurality of superposed continuous strips, certain of said strips having feed-arresting, form-registering physical alterations at predetermined intervals and being divided into a series of form lengths by transverse severing lines, and at least one other of said strips being comparatively narrow and terminating short of said alterations in transverse direction; a platen for supporting said strips; tensioning means for separately applying equal retarding tension to each of the superposed strips whereby one or more of said strips may be moved independently of the others; a main feeding means for advancing the first-named strips over said platen, said means being aligned with said physical alterations and cooperating therewith to interrupt advancement of said physically altered strips during each form-length feeding operation for registering the superposed form lengths of said strips; and feeding means for said other strip having a feeding surface engaging and advancing the other strip over said platen a predetermined distance, less than a form length of the physically altered strips and simultaneously advancing the physically altered strips to move said alterations beyond the main feeding means, whereupon the main feeding means again feeds the physically altered strips independently of said other strip.

8. In a manifolding register, a supply of stationery comprising a plurality of superposed continuous manifolding strips, the upper strips being transversely divided into a series of form lengths and having marginal and intramarginal feed-arresting, form-registering apertures in each form length, and the lowermost strip being relatively narrower than the upper strips and terminating transversely short of said marginal apertures, but extending over the intramarginal apertures; a platen for supporting the strips; a main feeding means comprising a pair of feed disks carried by a rotary shaft for advancing the upper strips over the platen, said feed disks being aligned with said marginal apertures and cooperating therewith to interrupt strip advancement during each form-length feeding operation to align the superposed form lengths of said upper strips before a severing line between successive form lengths reaches a predetermined position on the machine; and means on the rotary shaft for engaging said lowermost strip comprising a feeding shoe having a strip-engaging face of a length coextensive with the movement of said lowermost strip for advancing it a predetermined distance less than a form length for each rotation of the said shaft and for advancing all of said upper strips to move the marginal apertures thereof beyond the bite of the main feeding means, said shoe being carried by said shaft in alignment with the intramarginal apertures in the upper strips and cooperating with the intramarginal apertures thereof to interrupt advancement of the upper strips a second time during each form-length feeding operation for accurately registering the form lengths of the upper strips in transverse and longitudinal direction, the disks of said main feeding means having cutaway portions for temporarily releasing the upper strips during engagement of the last-

named means with said intramarginal apertures in the upper strips.

9. In a manifolding register, a supply of stationery comprising a plurality of superposed continuous detail strips transversely divided into a series of form lengths and having feed-arresting, form-registering apertures at the lateral margins thereof at form-length intervals and a relatively narrower summary strip disposed below said detail strips, terminating just short of said marginal alterations in transverse direction, and being substantially coextensive in breadth with the writing space of the detail strips; a platen for supporting said stationery; a main feeding means for advancing the detail strips a form length at a time over said platen, said means engaging the detail strips adjacent the margins thereof in alignment with said apertures, and cooperating with the latter to interrupt strip advancement during each form-length feeding operation for registering the superposed form lengths of the detail strips; and a starter member mounted on the main feeding means and positioned inwardly of the main feeding means for engaging the lowermost or summary strip to advance the detail strips to move the apertures therein beyond the main feeding means whereby the main feeding means again becomes operative to move said detail strips relatively to said summary strip during the remaining portion of the form-length feeding operation, said starter member having a feeding surface equal to the length of feed of said summary strip to feed said strip a predetermined distance less than a detail strip form length during each form-length feeding operation and being the sole means for advancing said summary strip.

10. In a manifolding register, a supply of stationery comprising a plurality of superposed continuous manifolding strips, the upper strips be-

40

ing transversely divided into a series of form lengths and having marginal and intramarginal feed-arresting, form-registering apertures in each form length, and the lowermost strip being relatively narrower than the upper strips and terminating transversely short of said marginal apertures, but extending over the intramarginal apertures; a platen for supporting the strips; a main feeding means comprising a pair of feed disks carried by a rotary shaft for advancing the upper strips over the platen, said feed disks being aligned with said marginal apertures and cooperating therewith to interrupt strip advancement during each form-length feeding operation to align the superposed form lengths of said upper strips before a severing line between successive form lengths reaches a predetermined position on the machine; and restarter means on the rotary shaft comprising a feed shoe for engaging the lowermost strip to advance all of the upper strips beyond the bite of the main feeding means and being carried by said shaft in alignment with the intramarginal apertures in the upper strips and cooperating with the intramarginal apertures thereof to interrupt advancement of the upper strips a second time during each form-length feeding operation for accurately registering the form lengths of the upper strips in transverse and longitudinal direction, the disks of said main feeding means having cutaway portions for temporarily releasing the upper strips during engagement of the last-named means with said intramarginal apertures in the upper strips, said shoe having a strip-engaging face of a length co-extensive with the required movement of the lowermost strip and advancing the same a predetermined distance less than a form length for each rotation of the shaft.

WILLIAM G. BORCHERS.
